UNITED STATES PATENT OFFICE.

GEORGE A. HOLM, OF MANSFIELD, OHIO.

PERFORATING-MACHINE.

SPECIFICATION forming part of Letters Patent No. 366,104, dated July 5, 1887.

Application filed July 9, 1886. Serial No. 207,595. (No model.)

To all whom it may concern:

Be it known that I, GEORGE A. HOLM, a citizen of the United States, residing at Mansfield, in the county of Richland, State of Ohio, 5 have invented certain new and useful Improvements in Perforating-Machines, of which the following is a specification, reference being had therein to the accompanying drawings.

My invention is a device for perforating paper. It is adapted to be applied or attached to any cylindrical printing-press.

Figure 1 is a transverse sectional view of my invention attached to the sides of a printing-press. Fig. 2 is an elevation of the device detached. Fig. 3 is a perspective view of the ends of two shafts and the hinged clamp rigidly uniting the same. Fig. 4 represents a plan fragmentary view of the cylinder and its circumferential band.

Like letters indicate like parts throughout the several views.

A indicates a shaft having its ends secured to the inner sides of the press frame.

B is a shaft lying parallel to the shaft A and secured thereto by means of the clamps C C. The clamps C are provided with two collars, C' C''. The collar C'' is provided with a hinged portion, C''. When the hinged portion C'' of the collar is closed it is secured to the clamp neck or shank by a bolt, D, said bolt passing through the hinged portion and clamp-neck, substantially as shown in Fig. 3. The collar C is provided with a threaded boss-opening for the reception of the threaded end 35 of the bolt E. The bolt E enters said opening, and when screwed in rigidly unites the shaft B with the collar C''. The collar C'', its hinged portion C'', and the bolt D serve to rigidly unite the shaft A and said collar.

F F represent two sleeves secured to the shaft B at any desired points by the set-screws F''. The set-screw passes through a threaded opening in the sleeve.

G represents an arm rigidly fixed to the sleeve F. This arm is provided with an opening on its upper end for the reception of the threaded bolt H.

H' is a threaded thumb-nut on the outer end of the bolt H.

I is a lug rigidly fixed to the sleeve F.

J is a bifurcated arm, having a perforating-wheel, K, journaled therein. The periphery

of this wheel is serrated, so as to perforate the paper when it is passed between said wheel and the press-cylinder. The outer end of the 55 bifurcated arm J is jointed at J' to the lug I.

L represents a spiral spring encircling the inner end of the threaded bolt H between the arms G and J.

The object of the jointed lug and arm I J, 60 bolt H, thumb-nut H', and spiral spring L is to regulate and adjust the pressure of the perforating-wheel K against the paper on the press-cylinder M—that is to say, the spiral spring L may be longitudinally expanded or 65 contracted by operating the thumb-nut H' and the pressure of the perforating-wheel K on the paper thereby increased or diminished at pleasure. The inner end of the bolt H is pivoted at h to the jointed arm J. 70 The periphery of the cylinder on the line of travel of the wheel K is provided with a circumferential band, M', of wood, lead, or other suitable material, to prevent the wheel from cutting into the cylinder while in 75 operation. The main shaft A having its inner ends fixed to the sides of the press, serves to strengthen and brace the press. By adjustably attaching the parallel shaft B to the fixed shaft A said shaft B may be firmly held in various positions. By means of the clamps C the shaft B and its connected mechanism may be laterally adjusted along the shaft A, or said shaft B and its attached parts may be swung 80 backward and downward, when desired—that 85 is to say, moved in the arc of a circle around the shaft A—whereby the perforating-wheels K may be adjusted in relation to the periphery of the cylinder.

The matter for printing is attached to the 90 revoluble cylinder by the clamping device now in use, or any suitable means. Before the paper reaches the type the said paper, by the movement of the cylinder, is passed between the rotary perforating-wheel K and the 95 periphery of the cylinder. The rotation of the cylinder rotates the perforating-wheel K, and thereby perforates the paper which passes between said wheel and cylinder. The paper is thereby perforated before it is brought in 100 contact with the type.

The sleeve F and its connected devices carrying the perforating-wheel is longitudinally adjustable on the shaft B, whereby said per-

forating-wheel may be caused to travel on any circumferential line on the periphery of the cylinder. Any suitable number of these devices may be placed upon the shaft K.

5 The shaft B may be rotated in clamps C to throw all of the perforating-wheels at once out of engagement with the cylinder, or said shaft may be removed in either case without disturbing the adjustment of the perforating-wheels on said shaft relative to each other.

I do not claim the band M', as that or other equivalent or preferred device may be used with the perforating apparatus.

Having thus described my invention, I claim as new and desire to secure by Letters Patent—

1. The combination, with the printing-press cylinder, of a perforating-wheel adapted to bear upon said cylinder, a movable bearing and support for the wheel, and a spring pressing upon the outer side of said support or bearing, whereby the wheel may be held against the cylinder with a yielding pressure, substantially as set forth.

25 2. A perforating attachment for printing presses, consisting in the combination of a jointed arm, provided on its outer end with a perforating-wheel, a bolt threaded on its outer end and having its inner end pivoted to said arm, a relatively-fixed arm provided with an opening for the reception of said bolt, a spring interposed between said arms, and a threaded nut on the outer end of the bolt aforesaid, substantially as specified.

35 3. A perforating attachment for printing-

presses, consisting in the combination of the fixed shaft A, parallel shaft B, and uniting-clamps, the shaft B being rotatable and longitudinally adjustable in the eyes C' of the clamp-bearings, and adapted to be clamped 40 therein at the desired point by set-screws F' of the rotatable sleeve F, longitudinally adjustable on the shaft B, said sleeve being provided with a lug having a spring actuated arm jointed thereto, the outer end of said arm being provided with a perforating-wheel, substantially as specified.

4. A perforating attachment for printing-presses, consisting in a fixed shaft lying parallel with the axis of the cylinder, a parallel 50 shaft, B, and clamps for connecting the two shafts, each of said clamps being provided with two collars for the reception, respectively, of the two shafts, one of the collars being provided with a hinged section and means, substantially as described, for locking the same, whereby the shafts may be held in a fixed relative position or the shaft B detached, in combination with an adjustable sleeve on the shaft B, said sleeve being provided with a lug 55 having a spring-actuated arm jointed thereto, the outer end of said arm being provided with a perforating-wheel, substantially as specified.

In testimony whereof I have affixed my signature in presence of two witnesses.

GEORGE A. HOLM.
